UNITED STATES PATENT OFFICE

129,939

DESIGN FOR A COIN ACTUATED CALENDAR BANK

George T. Kodama, Milwaukee, Wis., assignor, by
direct and mesne assignments, to John E.
Gaulke, Milwaukee, Wis.

Application August 22, 1940, Serial No. 94,552

Term of patent 7 years

To all whom it may concern:

Be it known that I, George T. Kodama, a citizen of the United States and a resident of Milwaukee, in the county of Milwaukee and State of Wisconsin, have invented a new, original, and ornamental Design for Coin Actuated Calendar Bank, of which the following is a specification, reference being had to the accompanying drawing, forming a part thereof.

Figure 1 is a perspective view of a coin actuated calendar bank, showing my new design, and

Fig. 2 is another view in perspective of the coin actuated calendar bank, showing my new design.

I claim:

The ornamental design for a coin actuated calendar bank, substantially as shown.

GEORGE T. KODAMA.
